MACHINE FOR GAUGING BOTTLENECK
OPENINGS

Anderson D. McNutt, Newark, and Robert L. Newton, Bridgeton, N. J., assignors to Owens-Illinois Glass Company, a corporation of Ohio

Application January 6, 1948, Serial No. 754

9 Claims. (Cl. 209—88)

1

Our invention relates to mechanism for testing or gauging as to shape or dimensions, various articles including bottles, jars and the like, and includes means for segregating defective articles from those which pass the test. The invention provides a machine for gauging articles fed thereto in rapid succession and automatically detecting and discarding defective articles.

The invention in the form herein illustrated and described comprises a machine designed and adapted for gauging the neck openings of bottles which are fed in rapid succession to the machine, and means for detecting defective bottles and automatically separating them from those which pass the test.

A primary object of the invention is to provide a machine which will detect and eliminate containers with undersize or deformed neck openings which would prevent satisfactory insertion of filling tubes such as used commercially in filling the containers.

Other objects of the invention will appear hereinafter.

Referring to the accompanying drawings:

Fig. 1 is a side elevation, with parts broken away, of a machine embodying our invention;

Fig. 2 is a plan view of the machine;

Fig. 3 is a wiring diagram of the electrical circuits for the motor and the apparatus for ejecting defective articles;

Fig. 4 is a cross-sectional elevation of the machine at the line 4—4 on Fig. 1 on a comparatively large scale;

Fig. 5 is a part-sectional plan view substantially at the line 5—5 on Fig. 4;

Fig. 6 is a sectional elevation at the line 6—6 on Fig. 5;

Fig. 7 is a fragmentary cross-sectional elevation at the line 7—7 on Fig. 5; and

Fig. 8 is an enlarged sectional detail showing the gauging plug testing a defective bottle.

Referring to Figs. 1 and 2, a brief description of the machine will now be given, followed by a more detailed description. The machine comprises, in general terms, a continuously traveling endless conveyor belt 10 and conveyor frame 11 mounted on a framework 12; an infeed device comprising a spiral timing feeder 13 by which the workpieces, herein shown as bottles B, are timed and centered under gauging heads 15 on gauging spindles 16. The gauging units, each comprising a spindle 16, are connected to upper and lower endless chains 17 and 18 for continuous travel horizontally in a closed path. The gauging spindles are mounted for up-and-down movement

under the control of a stationary cam 20 and each gauging spindle carries a gauging element in the form of a plug 21 (see Figs. 7 and 8) movable downwardly into the container for testing the neck opening. Each gauging spindle carries a detector comprising a pivoted arm 22 or tumbler which is thrown to a switch-operating position (as hereinafter described) when the downward movement of a gauging plug into the neck of a container is prevented. A switch 25 (Figs. 2 and 3) is arranged to be tripped by the tumblers 22, thereby closing an electrical circuit for an electromagnet 24 and causing the latter to operate an ejector 23 located at the ejecting station. A stationary cam 26 resets the trip arms 22.

The endless belt conveyor 10 is driven by a continuously running electric motor 27 (Fig. 1) operating through a train of gearing including speed reduction gearing in a gear box 28, a driving chain or belt 29 driving a vertical shaft 30 and bevelled gear 31.

The latter drives a gear 32 on a horizontal shaft 33 (Fig. 2) which has driving connection through a sprocket chain 34 with a drive shaft 35 for the conveyor belt 10.

The spiral conveyor 13 is driven by the motor 27 operating through a horizontal shaft 36 extending from the gear box 28, bevel gears 37, 38, and a vertical shaft 39 geared to the spiral conveyor 13.

The bottles B are fed onto the conveyor belt 10 at the righthand end thereof and are advanced with the conveyor between the spiral feeder 13 and a stationary guide rail 40. The timing feeder 13 is formed with a spiral thread 41 by which the bottles are accurately spaced and positioned to be brought into register with the gauging heads 15. The guide rail 40 is adjustably mounted by means of brackets 42 permitting adjustment for containers of different diameters.

The upper and lower sprocket chains 17 and 18 to which the gauging units are attached are trained respectively over upper and lower driving sprocket wheels 43 and 44 mounted on the drive shaft 30. The sprocket wheels have a splined connection with the drive shaft by means of splines or keys 46 secured to the sprocket wheels and engaging vertical grooves 47 in said shaft, permitting vertical adjustment of the gauging mechanism to accommodate workpieces of different heights.

The sprocket chains 17 and 18 are also trained over upper and lower driven sprocket wheels 48 and 49 (Fig. 1) mounted on a vertical shaft 50 and also having a splined connection therewith to permit such vertical adjustment of the gauging mechanism. The shafts 30

and 50 are journalled at their lower ends in bearings 51 on a lower platform 52 on the framework 12, and at their upper ends in bearings 53 secured to a horizontal frame bar or plate 54 (Figs. 1 and 2). The plate 54 forms part of an upper framework or superstructure 55 mounted on a platform 56 and in which framework the gauging mechanism is supported.

The gauging mechanism is suspended from the plate 54 by means of a pair of vertical shafts 58 which extend through openings in said plate and have keyed thereto bevelled gears 59 supported on the said plate. The gears 59 mesh with gears 60 keyed to a horizontal shaft 61 journalled in brackets 62. The shafts 58 extend downwardly through a horizontal plate 63 (Figs. 4 to 6) and have a screw-threaded connection with nuts 64 attached at the lower side of the plate 63. The gauging mechanism is supported from the plate 63 as presently described. The shaft 61 is provided with a hand crank 65 for rotating the shafts 61 and 58 and thereby adjusting the gauging mechanism up and down. The shaft 61 is also connected through bevelled gears 66, 67 to a vertical shaft 68 which has a screw-threaded connection 69 with the frame which carries the electromagnets 24 and ejector mechanism 23, for adjusting such mechanism up and down with the gauging mechanism.

Each gauging spindle 16 comprises a vertical tubular shaft including upper and lower sections 70 and 71 (Figs. 4, 7 and 8) having a telescopic connection permitting free relative vertical movement of said sections. The downward movement of the section 71 is limited by stop shoulders 72. The gauging head 15 comprises a disk 73 attached by welding to a nut 74 threaded on the lower end of the section 71 and held in position by a locking nut 75. The disk 73 is formed with an opening through which the gauging plug 21 extends, the walls 76 of said opening being upwardly tapered and thereby providing a frusto-conical surface adapted to engage the bottle neck as the gauge is lowered and accurately register the gauge with the bottle, preliminary to the testing operation.

Each gauging unit comprises a carriage 77 in which the spindle 16 is mounted for vertical movement. The carriage 77 is in the form of a casting comprising an upper head 78, lower head 79 and horizontally spaced vertical bars 80 integral therewith. The gauging spindles and their carriages 77 are supported during their travel on a track comprising parallel rails 81 at opposite sides of the plate 63, the track including end sections 82 concentric with the sprocket gears about which the chains 17 and 18 travel. The rails 81 are bolted to a bracket 83 seated on the plate 63 and attached thereto by bolts 84. Rollers 85 running on the tracks 81 are journalled on the heads 78 of the carriages. Attached to each head 78 is a bracket 86 carrying a roll 87 running on the inner vertical face of the track 81 and a pair of rolls 88 running on the outer face of said track. The lower head 79 of the carriage has secured thereto a bracket 90 carrying rolls 91 and 92 corresponding to the rolls 87 and 88 and running on guide rails 93 bolted to a lower bracket 94. The carriages are thus held securely against lateral displacement or tilting movements during their travel. The sprocket chains 17 and 18 are attached to the carriages by means of plates 95 and bolts 96.

The sprocket wheels 43 and 44 run on ball bearings 120 carried at the upper and lower ends

of a non-rotating tubular shaft 121 through which the rotary shaft 30 extends. Spacing sleeves 122, 123 and 124 surrounding the shaft 121, hold the brackets 83 and 94 spaced from each other and from the sprocket wheels. The sprocket wheels are mounted directly on a tubular shaft 125 surrounding the shaft 30 and connected thereto by the keys 46, the shaft 125 being interposed between the shaft 30 and the shaft 121. Nuts 126 and 127 threaded on the upper and lower ends respectively of the shaft 125 clamp the non-rotating parts together and to the stationary supporting plate 63. Vertical rods 128 extend through the tubular shafts 30 and 50, and are attached at their upper ends to the plate 54 and at their lower ends to the platform 52.

Each gauging plug 21 has a screw-threaded connection 97 (Fig. 7) with a tubular stem 99, the plug and stem being free for up-and-down movement within the shaft 70. The downward movement of the plug is limited by a nut 100 attached to the stem 99 at the upper end thereof in position to seat on the upper end of the shaft 70. Connections between the cam track 20 and shaft 70 include a cam follower roll 101 mounted on a stud shaft 102. The latter is formed with a collar 103 by which it is clamped to the shaft 70. A roll 104 journalled on the shaft 102 is positioned between the vertical frame members 80 on which it runs during the up-and-down movement of the gauging spindle, holding the latter against rotative movement.

During the forward travel of the gauging spindles over and with the containers B, the rolls 101 run on the cam track 20 which, as shown in Fig. 1, includes a downwardly inclined section 20a which permits lowering of the gauging spindle into engagement with the container, the conical surface 76 serving to accurately align the container with the spindle. When the gauging head seats on the container and is thus held from further downward movement, the upper section 70 of the spindle and the stem 99 with the gauging plug 21 continue their downward movement so that the plug is projected through the neck of the bottle to the dotted line position, Fig. 7. If the neck opening is too small to permit the full downward movement of the plug or has a constriction or malformation as at 105 (Fig. 8) obstructing and arresting the plug, the downward movement of the shaft section 70 relative to the plug causes a relative upward movement of the stem 99. This operates to throw the tumbler or detector arm 22 inwardly from the full line position to the operative position shown in dotted lines (Fig. 7), the said arm being connected by a pivot 106 to a bracket 107 clamped to the shaft 70.

The switch 25 (Fig. 2) has a trip arm 108 extending into the path in which the arm 22 travels when the latter has been thrown to said operative position, so that when the arm 22 reaches the switch 25, the switch is operated to establish a circuit for the electromagnet 24.

Referring to Fig. 3, the motor M is connected through a switch 110 in a three-phase system comprising mains a, b, and c. The electromagnet 24, when energized, operates the ejector 23 attached by an arm 111 to a core of the electromagnet. When the detector arm 22, which has been actuated by a defective bottle as above described, reaches the trip arm 108 and momentarily closes the switch 25, the said bottle has reached the position B' in the path of the ejector 23, so

that the electromagnet operates to eject the defective bottle from the conveyor.

The detectors or tumblers 22 which have been actuated by defective ware are reset by the cam 26 which is formed with an inclined cam surface 115 (Fig. 6) in the path of the tumblers. The cam 26 is attached to a bracket 116 bolted to the plate 63.

Modifications may be resorted to within the spirit and scope of our invention.

We claim:

1. Gauging apparatus comprising a tubular spindle including telescoping sections, each of said telescoping sections being freely movable with respect to the other, and to its mounting, means for mounting the spindle in upright position, a gauging head mounted on the lower said section at the lower end thereof and adapted to seat on an article under test, a gauging plug, a stem to which the plug is connected, said stem extending lengthwise through said spindle, said plug and stem being mounted for free sliding movement up and down relative to said gauging head and lower sections of the spindle to and from a gauging position, and a detector mounted on the spindle and projecting into the path of said stem and movable thereby to an operative position by relative movement of said stem and spindle.

2. Gauging apparatus comprising a tubular spindle including telescoping sections, means for mounting the spindle in upright position, a gauging head mounted on the lower said section at the lower end thereof and adapted to seat on an article under test, a gauging plug, a stem to which the plug is connected, said stem extending lengthwise through said spindle, said plug and stem being movable up and down relative to the spindle to and from a gauging position, and a detector mounted on the spindle and projecting into the path of said stem and movable thereby to an operative position by relative movement of said stem and spindle, said gauging head being formed with upwardly convergent guiding surfaces arranged to contact the article to be gauged as said head is moved downward and hold said article in register with the spindle.

3. Gauging apparatus comprising a tubular spindle including telescoping sections, means for mounting the spindle in upright position, a gauging head mounted on the lower said section at the lower end thereof and adapted to seat on an article under test, a gauging plug, a stem to which the plug is connected, said stem extending lengthwise through said spindle, said plug and stem being movable up and down relative to the spindle to and from a gauging position, a detector comprising a tumbler pivotally mounted on the upper section of said spindle and projecting over said stem, and means for moving said upper section downwardly while the gauging head is seated on the said article, said stem and gauging plug being free to move downwardly with the telescoping section for moving the gauging plug to a gauging position, said stem being operative to throw the tumbler when the gauging plug is prevented from completing its said downward movement to said gauging position.

4. Apparatus for gauging the neck openings of hollow articles, comprising a horizontally traveling conveyor, means for driving the conveyor, gauging mechanism including a plurality of gauging units mounted above the conveyor, each said unit comprising a vertical spindle and a gauging head carried by the spindle, means for driv-

ing the gauging mechanism in synchronism with the conveyor and causing the said spindles to move in a closed path with the spindles directly over the said conveyor during a portion of their travel, said spindles and gauging heads being movable downwardly to cause said heads to seat on articles carried on the conveyor, each said gauging unit including a gauging plug movable downward by gravity relative to the gauging head for causing the gauging plug to enter the neck opening of the article, a stationary cam track, cam followers individual to the gauging units and operatively connected to the said spindles for controlling their up-and-down movements, detectors carried with and individual to the spindles, each detector comprising a tumbler pivotally connected to the spindle, operating means between each gauging plug and its associated tumbler for throwing the latter to an operative position when the gauging plug is prevented from normal downward movement into a said neck opening, an electromagnet, a switch in circuit with the magnet winding and positioned in the path of the tumbler when the latter is in operative position, and an ejector operatively connected to and operated by said electromagnet.

5. Apparatus for gauging the neck openings of bottles or other articles, said apparatus comprising a horizontally traveling conveyor, gauging mechanism mounted above the conveyor and comprising gauging units mounted to travel horizontally in a closed path, means for driving the gauging mechanism and conveyor in synchronism, each said unit comprising a vertical spindle and a gauging head on the lower end of the spindle, said heads and spindles mounted for up-and-down movement during their travel for seating the gauging heads on the said articles and causing them while seated to advance with the said articles during a portion of their travel, each spindle comprising telescopically connected tubular sections, the lower section carrying the said gauging head, a stationary cam track, each said unit including a cam follower roll running on said track and connected to the upper telescoping section, said track being shaped to lower the spindle and seat the gauging head on an article to be tested and then move the upper said telescoping section downward relative to the gauging head, a gauging plug movable downward through the gauging head and into the neck opening of the article, a stem on which the gauging plug is connected, said stem extending upwardly through the spindle and movable up and down relative thereto, a tumbler pivotally connected to the upper telescoping section and projecting into the path of said stem and arranged to be thrown to an operative position by upward movement of said stem relative to the spindle, and ejector mechanism actuated by said tumbler, said ejector mechanism being positioned and arranged to eject articles from the said conveyor.

6. The gauging apparatus defined in claim 5 wherein the ejector mechanism comprises an electromagnet, an ejector arm operatively connected thereto, a switch in circuit with the electromagnet winding and positioned in the path of said tumbler when the latter is in operative position, and a stationary cam positioned and arranged to reset the tumblers.

7. Gauging apparatus comprising a vertical spindle, a supporting frame in which the spindle is mounted for up-and-down movement, said spindle comprising tubular telescoping sections,

each of said telescoping sections being freely movable with respect to the other, and to its mounting, a gauging head attached to the lower end of the lower said section, said head formed with an opening therethrough with upwardly tapered walls for engaging and centering an article to be gauged, a gauging plug mounted for free movement up and down through the opening in said head, a stem connected to said plug and extending vertically through the spindle and mounted for free sliding movement up and down relative to the spindle, and a stop device attached to the upper end of the stem in position to engage the spindle and limit the downward movement of the gauging plug relative to the spindle, the gauging plug when at said limit of downward movement being in a position in which it protrudes downwardly through the opening in the gauging head, and being free for upward movement relative to the spindle sections.

8. Gauging apparatus comprising a spindle including tubular telescopically connected sections, each of said telescoping sections being freely movable with respect to the other, and to its mounting, a carriage in which the spindle is mounted in vertical position, said spindle as a whole being movable up and down in the carriage, means for driving the carriage in a horizontal path, a stationary cam track, means providing operating connections between the cam track and the upper said section of the spindle, said track being shaped and arranged to effect up-and-down movements of the spindle during the travel of the carriage, a gauging plug, a stem attached to the plug and extending vertically through the spindle and mounted for up-and-down movement relative thereto.

9. Gauging apparatus comprising a spindle including tubular telescopically connected sections, each of said telescoping sections being freely

movable with respect to the other, and to its mounting, a carriage in which the spindle is mounted in vertical position, said spindle as a whole being movable up and down in the carriage, means for driving the carriage in a horizontal path, a stationary cam track, means providing operating connections between the cam track and the upper said section of the spindle, said track being shaped and arranged to effect up-and-down movements of the spindle during the travel of the carriage, a gauging head carried on the spindle at the lower end thereof and formed with an opening therethrough, a gauging plug mounted for up-and-down movement within said opening, a stem attached to said plug and extending upwardly through the spindle and mounted for up and down movement relative to the spindle, and a detector projecting into the path of the said stem and operable by the movement of said stem relative to the spindle.
